(57) **CLAIM**

The ornamental design for an paperweight, as shown and described.

DESCRIPTION

FIG. 1 is a front view of the paperweight, showing my new design;

FIG. 2 is a bottom view thereof;

FIG. 3 is a top view thereof;

FIG. 4 is a left side view thereof, the right side being a mirror image thereof;

FIG. 5 is a bottom perspective view thereof;

FIG. 6 is a top perspective view thereof; and,

FIG. 7 is a cross-sectional view thereof, taken along the line 7—7 in FIG. 3.

The broken lines in FIG. 7 are included for the purpose of illustrating portions of the interior that form no part of the claimed design.
